[57] **CLAIM**

The ornamental design for a rear window replacement module for an automobile, as shown and described.

DESCRIPTION

FIG. 1 is a perspective view of a rear window replacement module for an automobile showing my new design;

FIG. 2 is a top plan view thereof;

FIG. 3 is a right side elevation view thereof; the left side elevation view is a mirror image thereof;

FIG. 4 is a bottom plan view thereof;

FIG. 5 is a rear elevation view thereof; and,

FIG. 6 is a front elevation view thereof.

The broken line showing of a portion of an automobile in FIG. 1 of the drawing is for illustrative purposes only and forms no part of the claimed design.
